(Cl. D67—3)

To all whom it may concern:

Be it known that I, Raymond Loewy, a citizen of the United States, residing at New York city, in the county of New York and State of New York, have invented a new, original, and ornamental Design for a Lid for a Refrigerator Cabinet or Similar Article, of which the following is a specification, reference being had to the accompanying drawing, forming part thereof.

In the drawing:

Fig. 1 is a top plan view of a lid for a refrigerator cabinet or similar article, showing my new design;

Fig. 2 is a front view;

Fig. 3 is a side view;

Fig. 4 is a rear view; and

Fig. 5 is a perspective view thereof.

I claim:

The ornamental design for a lid for a refrigerator cabinet or similar article, as shown.

RAYMOND LOEWY.
